(57) **CLAIM**

The ornamental design for a grip with adjustable trigger spacer as shown and described.

DESCRIPTION

FIG. 1 is a FRONT PERSPECTIVE view of a design for the grip with adjustable trigger spacer;

FIG. 2 is a REAR PERSPECTIVE view thereof;

FIG. 3 is a FRONT view thereof;

FIG. 4 is a BACK view of thereof;

FIG. 5 is a TOP view thereof;

FIG. 6 is a BOTTOM view thereof;

FIG. 7 is a SIDE view thereof;

FIG. 8 is a SIDE view thereof;

FIG. 9 is a FRONT EXPLODED view thereof; and,

FIG. 10 is a BACK EXPLODED view thereof.

In FIGS. 9 and 10, the evenly spaced broken lines represent the portions of the design that form no part of the claim.
